VICTOR H. HABBERT, OF CHICAGO, ILLINOIS, ASSIGNOR TO TRANSERV CORPORATION, OF CHICAGO, ILLINOIS, A CORPORATION OF ILLINOIS

BRAKE SHOE WEDGE MEANS

Application filed May 20, 1932. Serial No. 612,529.

My invention relates to means which are especially adapted to present day standard brake heads and brake shoes for the purpose of firmly anchoring the shoes to the heads 5 against undue play and wear producing movement of the shoes relative to the heads encountered during train operation.

My invention also has for its object the provision of more or less inexpensive means 10 which may be easily applied to the brake heads to relieve the latter of wear and hence obviate the necessity of replacement of the more expensive brake heads; my improved means being such that replacement thereof 15 may be readily accomplished.

The invention also contemplates means whereby proper positioning of the means relative to the head and the shoe will be induced; wedging action on the shoe locking 20 key effected; holding relation with the head lugs also easily provided; while the entire upper face of the head lug which carries the weight of the shoe will be protected; said means being adapted to new and worn heads 25 and the usefulness of the heads thereby greatly enhanced.

The objects and advantages of my invention will be readily comprehended from the following detailed description of the drawings; wherein:—

Figure 1 is a perspective view of the forward or shoe receiving face, with the shoe weight receiving lug shown provided with one form of my wedge means.

Figure 2 is a vertical sectional view of the brake head and shoe, with the wedge means of Figure 1 applied and in section.

Figure 3 is a perspective view of the type of wedge means shown in Figures 1 and 2, 40 with portions broken away.

Figure 4 is a perspective view of the shoe side of a brake-head with a worn shoe sustaining lug and provided with a modified type of my improved wedge means.

Figure 5 is a perspective view of the type of wedge means employed in Figure 4, with a portion broken away.

Figure 6 is a perspective view of the rear 50 side of the type of brake shoe employed with the heads shown in Figures 1 and 4.

Figure 7 is a perspective view of another form of my improved wedge means.

Figure 8 is a similar view of a further modification of the wedge means.

My improved wedge means is especially 55 intended for the standard type of brake heads and shoes at present in use on railroads and is so constructed that they can be easily applied, whether the head is new or worn, without necessitating any change 60 or alteration in the head and shoe construction.

For reasons of economy and to permit interchange, the railroads adopted a standard type of brake head and shoe in so far 65 as general shape and dimensions are concerned, namely a brake head as shown at 15 in Figures 1, 2 and 4, and a shoe as shown at 16 in Figures 2 and 6.

In this standard type, the brake shoe is 70 provided on its rear face with the arcuate lugs 17, 17 in which the ends of a short strap or metal plate 18 are embedded during casting. These lugs 17, 17, with the strap 18, are intended to fit into the recess 75 of the head 15 provided between the vertically slotted lugs 19 and 20 of the head. The strap 18 in the shoe is arranged at a distance removed from the main rear face of the shoe 16 to provide a key receiving 80 passage or slot which is intended to register with the slots in the head lugs 19 and 20 for the purpose of receiving the shoe locking key or pin 21.

The heads and shoes generally consist of 85 more or less rough castings with certain tolerances in manufacture so as to enable easy insertion of the shoe lugs 17, 17 between the head lugs 19 and 20. As a result, a tight fit between the head and shoe lugs is 90 never provided, but, on the other hand, considerable play between head and shoe is permitted. With the shoes generally made of hard cast iron and the heads of malleable iron and therefore softer material, the 95 play or vibration of the heavy shoe (whose weight is carried mainly by the lower head lug 20) during train motion soon causes the shoe lugs 17, 17 to cut into and wear away the upper supporting face of the lower head 100

lug 20, namely the portions of the head lug 20 on opposite sides of the key receiving slot therein due to the contact therewith of the arcuate lugs 17, 17 at opposite ends of the strap 18 of the shoe. This constant vibration of the shoe causes the head lug 20 to become so worn that renewal of the heads is required at comparatively short intervals and hence entails considerable expense and loss of service time for the freight cars; and, before such repairs are made, allows the shoes to have excess travel independently of the heads during brake application.

15 My improved means are devised to overcome this serious difficulty and to provide a firm relation between the head and shoe lugs so that wearing vibration or movement between these members is prevented.

20 In the first three figures of the drawings, I illustrate a form of my improved wedge means adapted to new heads and shoes or slightly worn heads; the means involving a hard metal plate 22 provided with a 25 straight forward edge in keeping with the forward face of the shoe supporting lug 20 of the head. The plate is of length corresponding with the width of the head lug 20 so as to extend from side to side of the 30 head; and the plate at opposite ends is provided with the depending portions 23, 23, of length somewhat greater than the thickness of the head lug 20 so as to depend therebeneath. The portions 23, 23 are 35 integral and coincident with the forward straight edge of the plate, with the lower ends of the portions 23 preferably slightly beveled or tapered rearwardly so as to properly clear the rear face of the applied shoe 40 16; and these tapered lower ends are then bent inwardly beneath the head lug 20 as shown at 24 in Figure 1, thereby holding the plate against vertical movement.

The intermediate rearwardly enlarged 45 portion of the plate is shown provided with a transverse cavity on its lower or head lug engaging face, as shown at 25 in Figure 3. In the particular exemplification of the invention, as shown in Figures 2 and 3, this 50 cavity is provided by bending the plate slightly upward, as shown at 26; the raised portion extending from front to rear and of width corresponding with the distance between the two arcuate lugs 17, 17 on the 55 shoe, thus permitting this raised portion 26 to fit between the shoe lugs 17, 17, without, however, contacting or interfering with the lug-strap 18 of the shoe.

By constructing the intermediate portion 60 of the plate in this manner, the plate is equally as well adapted for use on a slightly worn brake-head, as the cavity or recess 25 on the lower face of the plate will then accommodate the intermediate portion of 65 the head lug 20 which lies beneath the spac-

ing intermediate of the shoe lugs 17, 17 and therefore is not worn; while the major portion of the plate will cover the slightly worn portions of the head lug on opposite sides of the median line and hence the major portion of the plate may extend in a horizontal plane beneath that of the unworn intermediate part of the head lug 20. On the other hand, if the head lug is unworn, then the raised intermediate portion of the plate will 70 extend into the socket or space between the shoe lugs 17, 17, without interfering with the proper use of the plate on a new head. At the same time, this raised portion 26 of the plate will also induce the proper positioning 75 of the plate and assist against any tendency to lateral displacement.

The plate 22, intermediate of opposite ends, is widened or enlarged; the enlargement adjacent opposite ends being made 80 arcuate as shown at 27; the curvature corresponding with the curved sides of the shoe lugs 17, 17 (see Figure 6). The arcuate portion of the plate is thus adapted to the 85 contour of the cavity that is worn into the head by the shoe lugs 17, 17.

The intermediate portion of the plate, 90 namely the recess forming raised portion 26, at a point adapted to register with the locking key receiving sockets or passages in the head lugs, is provided with a suitable opening or slot 28 for passage of locking key 21 therethrough; and where the means or plate is made of comparatively thin sheet metal, the portion of the metal partially severed 95 from or stamped out of the plate to form the key opening 28, is bent downwardly along the forward longitudinal line or wall of the slot, to provide a depending tongue 29 which will extend substantially parallel with the forward face of the key 21 and cause the latter to be forced slightly rearwardly toward the head and hence induce the shoe lugs 17, 17 to be forced rearwardly between 100 the head lugs 19, 20 and hold the rear face 105 of the shoe in firm relation with the head.

In Figures 4 and 5 I show a type of wedge means 30 more especially intended for use where excessive wear has occurred on the head lugs 20 and therefore a somewhat thicker plate is employed. The wedge means 30 may be of cast metal and in general contour, is substantially similar to the plate 22 heretofore described; having depending portions 31, 31 coincident with the 110 forward straight edge of the plate; the lower ends of these portions 31, 31 being intended to be slightly bent beneath the head lug 20 as shown in Figure 4 after the plate 115 is properly positioned.

This plate 30 is cast with a slightly raised intermediate portion or boss 32 on its upper face, adapted to extend between the shoe lugs 17, 17 and thus assist in positioning the plate and in holding it in place. This raised 120 125 130

portion or boss 32 is shown rearward of the longitudinal median line of the plate and is provided with a locking key slot or passage 33. This plate may be made of cast metal 5 and has the forward straight edge shown provided with a recess or cut-out portion at 34; and the forward side or wall of the boss 32 is extended downwardly beneath the plate to provide a tongue 35, which is also disposed 10 in vertical alignment with the forward side of the key slot 33 and therefore functions in the same manner as the tongue 29 of the previously described plate 22. The recess or slot 34 registers with the space 15 between the shoe lugs 17, 17 and hence is at a point where the unworn part of the head lug 20 may extend into the recess 34.

In Figures 7 and 8 I show other modifications of my improved wedge means involving comparatively heavy plates 36 and 37 which may be forged into shape and which, like the structure shown in Figures 4 and 5, are especially intended for use where more or less excessive wear on the head lug has occurred sufficiently to accommodate a plate of the thickness of these types. The plates 36 and 37 are both of uniform thickness and provided with flat faces and the plates are formed with the rearwardly disposed portions having the arcuate perimeters as at 38 at opposite ends in keeping with the arcuate formation of the shoe lugs 17, 17, see Figure 6, so as to fully extend throughout the shoe lugs and receive the 35 wear and strains therefrom.

The forward straight longitudinal side of the plate 36, intermediate of the ends, namely at a point which will be coincident with the spacing between the shoe lugs 17, 17, may 40 be cut away as shown at 39, if desired; while the rearwardly bowed or extended portion of the plate is provided with an elongated opening 40 which is adapted to register with the spacing between the shoe lugs 17, 17, 45 rearward of the connecting strap 18 of the shoe, for the purpose of receiving the shoe locking key 21; the slot or elongated opening 40 being spaced from the recess or cut out portion 39 by an intervening reenforcing 50 web or portion 41; whereas in Figure 8, this intervening web portion 41 is shown omitted. With the plate 37 of sufficient thickness, namely somewhat heavier than plate 36, a single recess 42 may be provided for passage 55 of the shoe locking key 21; the recess 42 terminating somewhat farther removed from the rear side of the plate than is true of the slot 40 in plate 36.

The locking key 21 is normally provided 60 with a slight forward curvature, but during insertion has a tendency to flex and straighten and thus have less firm holding action. The portions of the various forms of means, rearward of the key receiving passages, however, tends to force the lower end of the key

toward the shoe and hence cause the shoe to be more firmly drawn toward the head. Where the wedge means are provided with the depending tongues, as in Figures 1 and 4, these tongues extend lengthwise of the forward faces of the keys and increase the binding action and hence prevent any chattering tendency of the shoe and therefore eliminate possibility of rapid wear of the head lug 20.

The plates 36 and 37, like the other forms, are provided with the depending legs or portions 43 of narrower width than the plate proper and arranged coincident with the forward straight longitudinal side as shown so as to clear the forwardly curving head; the legs 43 being of length sufficient to extend slightly beneath the head lug 20 in order that the legs may be bent therebeneath, as shown in Figures 1 and 4.

With the recesses at the forward longitudinal sides of the plates, as shown in Figures 4, 7 and 8, or the recess in the intermediate portion as provided on the lower side of the plate 22 in Figure 1, all of which will be disposed beneath the recess intermediate of the two shoe lugs 17, 17, the plates are adapted to receive any upstanding unworn central portion on the head lug 20, thus permitting the plates to lay substantially flat on the head lug 20.

I have shown various embodiments of my invention and have described the same in terms of description, but certain modifications may be made without, however, departing from the spirit of my invention.

What I claim is:

1. Brake shoe wedge means comprising a plate portion adapted to be disposed between the opposing faces of the supporting lugs of a brake head and brake shoe, the plate being of greater width intermediate of its ends and curving rearwardly to fit into the recess in the forward face of the brake head, the intermediate portion of the plate having a key receiving passage, while the ends of the plate coincident with the forward longitudinal edge thereof are disposed downwardly to straddle opposite sides of the head lug.

2. Brake shoe wedge means comprising a plate adapted to be disposed between the opposing faces of the supporting lugs of a brake head and brake shoe and being of greater width intermediate of its ends and curving rearwardly to fit the recess in the forward face of the brake head, the intermediate portion of the plate being formed to receive the intermediate non-wear receiving portion of the brake head lug and to receive the shoe locking key; the ends of the plate coincident with the forward edge of the plate having downwardly disposed legs adapted to straddle opposite sides of the head lug and to extend therebeneath.

3. Brake shoe wedge means comprising a plate adapted to be disposed between the opposing faces of the supporting lugs of a brake head and brake shoe and having a straight longitudinal edge at the forward side and a rearwardly curving portion intermediate of its ends, the forward part of the plate intermediate of its ends having a recess to receive the intermediate non-wear receiving portion of the brake head lug, said intermediate portion being also formed to receive the shoe locking key, and the ends of the plate having depending legs coincident with the forward side adapted to straddle opposite sides of the head lug and to extend therebeneath.

4. Brake shoe wedge means comprising a plate adapted to be disposed between the opposing faces of the supporting lugs of a brake head and a brake shoe and having a straight longitudinal edge at the forward side and a rearwardly curving portion intermediate of the ends, the forward side of the plate having a recess coincident with the non-wear receiving portion of the head lug, said intermediate portion being also formed to provide a shoe locking key passage, and the ends of the plate forward of the rearwardly curved portion having narrow depending legs coincident with the forward side adapted to straddle opposite sides of the head lug and to extend therebeneath.

5. Brake shoe wedge means comprising a plate adapted to be disposed between the opposing faces of the supporting lugs of a brake head and a brake shoe and having a straight longitudinal edge at the forward side and a rearwardly curving portion, intermediate of the ends, the intermediate portion of the plate being recessed at a point coincident with the non-wear receiving portion of the head lug, said intermediate portion being also formed to provide a shoe locking key passage, and the ends of the plate forward of the rearwardly curved portion having narrow depending legs coincident with the forward side adapted to straddle opposite sides of the head lug and to extend therebeneath.

6. Brake shoe wedge means comprising a plate adapted to be disposed between the opposing faces of the supporting lugs of a brake head and a brake shoe and having a straight longitudinal edge at the forward side and a rearwardly curving portion intermediate of the ends, the intermediate portion of the plate being recessed at a point coincident with the non-wear receiving portion of the head lug, said intermediate portion being also formed to provide a shoe locking key passage and having a depending tongue adjacent one side of said passage, and the ends of the plate forward of the rearwardly curved portion having narrow depending legs coincident with the for-

ward side adapted to straddle opposite sides of the head lug and to extend therebeneath.

7. Brake shoe wedge means comprising a plate adapted to be disposed between the opposing faces of the supporting lugs of a brake head and brake shoe and having a straight longitudinal edge at the forward side and a rearwardly curving portion intermediate of its ends, the plate being formed intermediate of its ends with a recess adapted to receive the upstanding unworn portion of the head lug, the intermediate portion of the plate also having a key receiving slot, while the ends of the plate terminate in narrow depending legs coincident with the forward straight edge of the plate.
